ROSIN PACKAGE

Charles Crum Gillican, Homerville, Ga., assignor,
by mesne assignments, to The Glidden Company,
Cleveland, Ohio, a corporation of Ohio

Application December 30, 1937, Serial No. 182,584

3 Claims. (Cl. 226—47)

The present invention relates to the packaging of rosin in cartons, said rosin being produced from any of the prior art materials and by any of the prior art methods. The present invention is applicable to gum rosin or to a rosin produced by steam distillation or destructive distillation of wood.

It is customary to package rosin, however produced, in wood or galvanized iron barrels. When wooden barrels are used, it is frequently necessary to seal the space between the staves with a clay composition. When the rosin is removed from the barrels, the latter is contaminated with some of the clay and the presence of this impurity in the rosin is in many cases objectionable. Another disadvantage of packaging rosin in barrels is that there is a very substantial loss of rosin. Usually, the barrel will contain about 400 pounds of rosin, and when the rosin is removed from the barrel, about 6 pounds is lost, since this amount of rosin adheres to the staves and head of the barrel.

Another disadvantage of the use of wooden barrels for the packaging of rosin is that a barrel containing about 400 pounds of rosin has a net weight of approximately 80 pounds, making the gross weight of the rosin and the barrel approximately 480 pounds. When these barrels are shipped, the shipper or the customer must pay freight not only on the rosin, but also on the weight of the barrel itself.

While the packaging of rosin in galvanized containers has certain advantages over the packaging of rosin in wooden barrels, there are also certain disadvantages inherent in the use of galvanized iron containers as compared to the use of wooden barrels. It takes about 24 hours, approximately, for the rosin to cool and solidify in wooden barrels, while it takes approximately 36 to 48 hours for the rosin to cool and solidify in galvanized iron containers. From a practical standpoint, this delayed cooling seriously interferes with the economic operation of the rosin plant, and for this reason alone, the packaging of rosin in galvanized containers has not come into general use. Further, comparing the packaging of rosin in galvanized iron containers with the packaging of rosin in wooden barrels, it may be pointed out that the wooden barrels can be handled before the rosin content has completely solidified, whereas the rosin content of the galvanized iron barrels must be allowed to solidify before the iron barrels can be rolled. If complete solidification is not attained, then the iron

barrels will on rolling be easily deformed, and this is objectionable.

Another objection to the use of galvanized iron barrels is that the barrel breakage during shipment is much greater than is the case with the wooden barrel. The iron barrel has the further disadvantage of high cost as compared to the wooden barrel. However, the wooden barrel in itself is expensive as compared to the rosin packaging of the present invention.

In accordance with the present invention, the difficulties inherent in the packaging of rosin in wooden barrels or galvanized iron barrels are overcome. The present invention is directed to the packaging of rosin in a paper container, such as a carton, said carton having as its essential constituent a paper base, said paper being derived from any of the usual cellulose sources. More specifically, the invention is directed to the herein disclosed novel method and package.

In accordance with the present invention, the rosin is introduced into a paper carton, the rosin being maintained at a temperature enabling the rosin to be easily poured while inhibiting any substantial absorption of the rosin by the container.

While the rosin may be maintained at a temperature between 150° F. and 350° F., the preferred range is between 240° F. and 280° F.

It is preferred that the walls of the carton which contact the rosin carry a coating or impregnation adapted to minimize the absorption of the rosin by the carton material. Of course, this coating or impregnating material should be substantially chemically inert with reference to the rosin. In other words, there should be no substantial reaction between the coating material and the rosin so as to destroy the value of the coating material. While sodium silicate has given very satisfactory results, instead of using this material, equivalents thereof well known in the art may be used, and in fact, as stated, any coating or impregnating medium may be used which will minimize the absorption of the rosin by the carton material, said medium being chemically inert towards the rosin and solid at the temperature of pouring of the rosin.

In general, the method consists of disposing a relatively stiff carton having a paper base as its essential constituent in a supporting frame adapted to prevent the side walls of the carton from bulging outward as the liquid rosin contained therein cools and solidifies, introducing the rosin into the so-disposed carton and cooling and solidifying the rosin in the carton while it

is disposed in the supporting frame to insure a substantially non-bulging carton.

From the standpoint of the novel package, the invention resides in a package comprising a container, such as a carton having as its essential constituent a cellulose material, such as a paper base, said container being inert towards the rosin at a temperature varying between 150° F. and 350° F., said paper container being characterized by the property of absorbing little liquid rosin, the container having present in situ solidified rosin, and in the preferred form, the carton has a coating of a material chemically and physically inert towards the rosin, while at the same time minimizing any tendency of the carton material to absorb rosin.

Preferably, the carton which is provided with bottom flap members and a top closure member, is made of corrugated board and provided with an inner lining. The inner edges of the bottom member is provided with corrugation pockets which are sealed to prevent the rosin in its liquid state from entering the corrugation pockets. These pockets are sealed with a sealing medium comprising a material physically and chemically inert with respect to the rosin and solid at the pouring temperature of the rosin. While sodium silicate has been found very satisfactory, it is not desired to be limited to this material, and other materials which are physically and chemically inert with respect to the rosin and solid at the pouring temperature of the rosin may be used in place of the sodium silicate. After the pockets are thus sealed, the edge wall of the bottom member is closed with a sealing strip, as hereinafter more fully described.

The present invention will be disclosed in connection with the following drawing, in which:

Figure 1 is a diagrammatic side view showing the packaging of the rosin in the carton, said rosin being derived from the primary cooling vat.

Figure 2 is a perspective view of the carton supporting frame with the carton therein disposed.

Figure 3 is a perspective view of the carton used for packaging the rosin.

Figure 4 is a horizontal sectional view through the carton looking in the direction of the carton bottom.

Figure 5 is a vertical section on the line 5—5 of Figure 4.

Figure 6 is a detail view showing the corrugation pockets sealed to prevent running into the pockets.

Figure 7 is a modification of a rosin supporting frame.

Referring to the drawing, and more specifically to Figure 1, rosin is distilled in stills 1 and 2, said stills being preferably heated by direct flame.

When the material being distilled, as for example, an oleo resin, reaches a predetermined temperature, approximately 210° F. the turpentine and the water present starts to distill over. The turpentine and water is condensed usually by means of a worm condenser immersed in a cooling bath, and the condensate is then passed into a gravity separating tank where the water and turpentine separate into two layers, the water being the bottom layer and the turpentine being the upper layer. The distillation in stills 1 and 2 is continued until practically all of the water present in the material undergoing distillation is distilled off. Additional water is added when the same is necessary. There remains after distillation in the stills 1 and 2 molten

rosin. It may be stated that usually after about 30 minutes, most of the original water present in the oleo resin has been removed. The still temperature at the beginning of the distillation step is around approximately 210° to 215° F. depending upon the character of the resin being distilled. This temperature is gradually increased until after about 30 minutes has elapsed, the temperature of distillation is between approximately 220° F. and 230° F. when treating virgin oleo resin, and approximately 230° F. to 250° F. when treating old oleo resin. As stated, about one-half hour after the start of distillation, water is introduced into stills 1 and 2, the function of the water being to facilitate the distillation of the turpentine from the oleo resin. As the distilling step progresses, the distillation temperature is increased until towards the end of the distillation the temperature varies approximately between 290° F. to 350° F., the preferable upper temperature being about 315° F. For some purposes, it is quite desirable to have a high melting point rosin and in order to produce the same, it is necessary to substantially eliminate turpentine and water, and this may be attained by heating to approximately 350° F.

While the distillation is desirably carried out under atmospheric pressure, it may be carried out under superatmospheric pressure, or even under a vacuum, and if a vacuum is used, high melting point rosins may be produced at lower temperatures.

In operating stills 1 and 2, about 4000 pounds of oleo resin is charged in each still. The period of distillation averages about two and one-half (2½) hours, thereafter the tail gates 3 and 4 are opened and the rosin is allowed to pass to receiving vats 5 and 6, said vats preferably containing straining means, although the straining means may be extraneous of the vats. From the vats 5 and 6, the rosin is pumped by means of pumps 7 and 8 to a cooling vat 9. The conduits 10 and 11 for conveying the rosin to the cooling vats are provided with steam jackets 13 and 14 to facilitate the flow of the rosin.

From the cooling vat 9 the rosin passes to a carton 15, said carton being supported in a frame 16, the carton being adapted to receive the liquid rosin from the conduit 17 provided with a valve 18. The supporting frame 16 carrying the carton 15 is positioned on scales 19. The front and rear walls 20 and 21, and the side walls 22 and 23 of the supporting frame 16 are provided with apertures 24 to facilitate the cooling of the rosin in the carton 15.

The carton 15 is preferably made of corrugated board provided with corrugations 25, said carton having 100% kraft liners 26 and outer cover boards 27. The side walls of the supporting frame function to prevent the carton walls from bulging outwardly, during the time the rosin is cooling in the carton. It is desirable that the side walls of the supporting frame function to prevent the side walls of the carton from bulging out because the carton 15 should preferably remain in the supporting frame until the rosin solidifies. If the carton 15 with its rosin content is removed from the supporting frame 16 prior to the substantially complete solidification of the rosin, the sides of the carton will bulge out due to the action of the liquid rosin.

The carton 15 is allowed to remain in its supporting frame 16 for a period of from approximately 12 to 18 hours, depending on the temperature of the atmosphere and the temperature at

which the rosin is initially introduced into the carton. The above figure is simply illustrative, and is not by way of limitation, as obviously the time of cooling and solidification of the rosin will depend on the characteristics of the rosin, the temperature of the cooling medium, and to some extent the conductive characteristics of the carton material. After the carton 15, the latter containing a charge of about 100 pounds, has been completely cooled and solidified, the top, front and rear flaps 15a, 15b and side flaps 15c and 15d are closed and a sealing strip 15e is placed across the closed front and rear flaps so as to seal the closure space between the adjacent inner edge walls of the flap members 15a and 15b. The carton is then ready for shipment.

The carton which has been found most satisfactory to carry out the present invention is the one that is manufactured by the Mengel Company, Inc. of Louisville, Kentucky, which has a bursting resistance limit of 200 pounds per square inch, said carton comprising a corrugated board 25 of about $\frac{1}{2}$ of an inch in thickness. The inner kraft liner 26 is approximately $\frac{1}{64}$ of an inch thick, and the outer cover board 27 is about $\frac{3}{64}$ of an inch thick. These specifications are merely given as illustrative of the characteristics of a suitable carton and are not to be taken by way of limitation. It is obvious that the thickness of the corrugated sheet itself, the inner kraft liner, and the outer board may be varied. These three (3) elements are securely glued together to form the composite carton.

It has been discovered that when the liquid rosin is put into the carton, there is a substantial tendency for the rosin to soak into the container material, and the higher the temperature of the liquid rosin, the greater the tendency of the rosin to be absorbed by the carton material, and particularly for it to be absorbed through the kraft liner or equivalent paper material. In order to minimize this tendency, it has been found highly desirable to coat the liner with a medium functioning to inhibit or to minimize the absorption of rosin by the carton material, said medium being physically and chemically inert towards the rosin and solid at the temperature at which the rosin is poured. As an example of a suitable coating material for the inner surface of the carton, mention may be made of ordinary sodium silicate, or water glass. It is obvious that having once ascertained that it is desirable to coat or impregnate the inner surface layer of the carton, that other coating materials will suggest themselves to those skilled in the art, and, therefore, it is not wished to be limited to the use of sodium silicate as the coating material. Equivalent chemical compounds or compositions well known in the art may be substituted therefor. It is only necessary that the composition function to prevent the rosin from being absorbed by the container material.

It is highly desirable in carrying out the present invention that the temperature of the rosin be sufficient to enable the rosin to be easily pourable and insufficient to cause the rosin to be absorbed by the material of the container 15 to any substantial extent. If the board has any substantial absorption characteristics for the rosin, then it is preferable, as hereinbefore set forth, to coat or impregnate the inner walls of the container with a medium which is physically and chemically inert towards the rosin and which is solid at the temperature at which the rosin is poured. Since fairly pure rosin, that is rosin

that does not have much turpentine or water left therein, has a softening point of around 158° F., it is desirable that the rosin should not be cooled lower than 150° F. In other words, the rosin, in order to carry out the present invention, must run, and even if a minor proportion of the rosin is solid, there will be a mixture of solid and liquid which is pourable. When operating with a fairly pure rosin, the rosin or any other resin, either natural or synthetic, ordinarily will be delivered to the receiving vats 5 and 6 at a suitable temperature usually varying between 290° F. and 325° F. Under some circumstances, the temperature of the liquid rosin may be somewhat higher or somewhat lower. The rosin, after passage to the cooling vat 9, is preferably allowed to cool to a temperature which will inhibit or minimize the absorption of the rosin by the carton material. Satisfactory results have been obtained when the rosin was poured in the carton at a temperature between 240° F. and 275° F. As the temperature is increased beyond 275° F. there is a tendency for the rosin to be absorbed by the carton material, and this tendency is greatest when the carton material does not carry a coating or impregnating medium. The tendency to be absorbed is minimized to some extent by the application of an absorption minimizing agent, such as hereinbefore set forth.

If the rosin is one that necessitates a high distillation temperature, and said distillation temperature is in the neighborhood of 350° F. or the distillation is carried to such a temperature during the latter part of the distillation operation, the resulting rosin may be packaged in cartons in accordance with the present invention. However, there will be some tendency for the rosin to be absorbed by the carton material, and if this tendency, depending on the qualities of the carton material and the chemical and physical characteristics of the rosin, is slight, there will be no substantial objection to employing the higher temperature limit of 350° F. In some cases, if this higher limit is employed, the objection to absorption can be eliminated by coating or impregnating the inner surfaces of the carton with a coating material which will minimize the absorption at a temperature of 350° F. Here again, the coating or impregnating material must be chemically and physically inert towards the liquid rosin and be non-soluble in the rosin at this temperature. Since sodium silicate has a high melting point, materially over 350° F. it will function satisfactorily as the coating and absorbing agent, even at this high temperature.

The lower temperature limit at which the rosin can be poured is in the neighborhood of the softening point of rosin or a little below. A fairly good rosin melts at 158° F. Therefore, the lower limit of the pouring-temperature can be placed at approximately 150° F.

It is exceedingly difficult to express the limits of the invention in terms of actual temperature, and moreover, it is not necessary. The temperature-control aspect of the present invention resides in correlating the temperature at which the rosin is poured with the absorption characteristics of the carton material, so that at the temperature utilized, there is no substantial absorption of rosin by the carton material. This is the difficulty that must be overcome and the criterion has been set forth by which the desired inhibition of absorption by the carton ma-

terial is attained. It is preferred, in accordance with the present invention, to keep the pouring temperature of the rosin to between 240° F. and 250° F.

In actual operation, the pouring operation is probably started at 260° F. or 275° F., and inasmuch as the cooling vat has about 2500 to 3000 pounds of rosin present, the filling of the respective cartons, each holding about 100 pounds, is finished at approximately a temperature of 10 about the softening point of the rosin. In other words, the filling operation is started at the maximum temperature compatible with the character of the carton material employed and the temperature decreases as successive cartons are 15 filled, the lower temperature being, as stated, in the neighborhood of the softening point of the rosin, or just a little above. There is an advantage in utilizing lower temperatures of pouring, as the colder the rosin is poured, the higher 20 the poundage content of the carton for a given volume. There is also the advantage that the carton will cool and solidify more quickly.

The temperature of pouring has an influence 25 on the symmetrical solidification of the rosin block. Due to the fact that the rosin cools in the carton in layers, when the rosin is finally cooled, there is a cup in the top surface of the rosin and the higher the temperature at which 30 the rosin is poured the greater the tendency for the upper surface layer of the rosin block to cup. It is preferred from this standpoint to keep 35 the temperature of pouring less than about 280° F. as this reduces the amount of cupping. The lower limit will be governed by practical considerations and it will suffice to state that the lower the temperature of pouring the less will be the tendency to cup, and if the temperature of pouring could be reduced, considering practical operation, to approximately at or near the 40 softening point of the rosin, there would be substantially no cupping of the upper surface layer of the rosin. Therefore, from the standpoint of cupping, the lower the temperature of pouring, the less the cupping.

When the packages are stacked one upon the other, there is an air space between the top cover members 15a and 15b of the carton and the cupped surface 28 of the rosin, and there is a tendency for the cover members 15a and 15b to be crushed. Therefore, in accordance with 45 the present invention, this tendency to cupping and the tendency of the packaged rosin to create difficulties in stacking, may be controlled by controlling the pouring temperature of the liquid rosin, the lower the pouring temperature, the less the cupping and the less difficulty there will be experienced in packing.

The carton utilized in carrying out the present 50 invention is provided with side walls 45 and 46, and front and rear walls 47 and 48. The bottom member of the carton is formed by turning over the flaps 15f and 15g, which are integrally formed at the lower bottom end of the side walls 45 and 46. Thereafter, the flaps 15h and 15j, which are 55 integrally formed with the walls 45 and 46, are turned over and the flaps then assume the position shown in Figure 4. It is to be noted that the bottom members 15f, 15g, 15h and 15j are composite members comprising a layer of corrugated board between two outer layers of board, the constituent elements of the composite board being of approximately the thickness hereinbefore described in connection with the side walls. It has 60 been discovered that when rosin is introduced into

the carton that there is a substantial tendency for the rosin to run through the inner edges of the members 15f, 15g, 15h and 15j into the corrugation pockets 29. It has been discovered that the loss of the rosin caused by the flowing of the rosin into the corrugation pockets can be eliminated by sealing the edge walls of the members 15f, 15g, 15h and 15j with sealing strips 30, 31, 32 and 33, these sealing strips being made of heavy paper. The strips 32 and 33 covering the edges of the members 15h and 15j extend laterally a short distance to form upper and lower facing members 34, 35, 36 and 37, respectively, as shown in Figure 5.

Any ordinary paste can be used for sealing the strips 32 and 33. The sealing strips for members 15f and 15g are constructed and applied in an identical sealing manner to the strips 32 and 33.

Instead of using sealing strips 30, 31, 32 and 33, the same result can be accomplished by applying to the edge members, as by dipping or the like, a chemical agent which will close the corrugation pockets. For example, a heavy solution of sodium silicate may be applied. The chemical agent will run back into each corrugation pocket for a short distance, as for example one-half inch, and fill the corrugation pocket. It is, of course, necessary that the filling agent for the corrugation be one that will not be melted at the temperature at which the rosin is poured. Sodium silicate admirably fulfills this purpose, as it has an exceedingly high melting point, much above that of the rosin.

Any sealing agent may be employed which is chemically and physically inert towards the rosin and which is not soluble in the rosin at the temperature at which the rosin is poured.

Another method of closing the corrugation pockets and preventing loss of rosin is to flatten the corrugations by pressure, said pressure being sufficient to cause the flattened corrugations and the inner and outer corrugation liners to become a substantially unitary member, incapable of being opened by the pressure of the liquid rosin in the carton. It may be stated that the carton is 18 inches in height, and the cross sectional dimensions are 9 inches and 18 inches.

The outer bottom members 15h and 15j of the carton after they have been treated and brought to their closed position, are fixed in place by a sealing strip of paper 38 or any other material which has sufficient strength to keep the bottom members 15h and 15j in the sealed position when the material has the liquid rosin or solidified rosin therein. After the bottom members of the carton have been treated as specified, the carton is placed in its supporting frame and is ready for receiving the liquid or molten rosin.

One advantage inherent in the packaging of the rosin in a carton of the character herein described is that the cartons lend themselves to easy storage and shipment, in that they are symmetrical and stack well.

Instead of using a supporting frame, such as set forth in Figure 2, the pouring and cooling and solidification steps may be carried out while the carton is in a supporting frame such as shown in Figure 7, where the supporting frame 39 on all its sides is provided with heavy reinforced mesh wire 40, the wire having sufficient strength to prevent the carton sides from bulging out upon introduction of the rosin into the carton, said mesh sides simultaneously affording contact with the colder atmospheric air in order to facilitate cooling and solidification.

It is within the province of the present invention to use any container which has a paper base, that is, in which the essential constituent is paper or paper pulp. It is recognized that there may be admixed with the paper pulp other constituents, but these constituents must be relatively inert to the liquid or molten rosin. Of course, the carton material must not char at the temperature of the molten rosin, or in any manner have its tensile strength reduced by contact with the molten rosin. Further, there should be substantially no chemical interaction with the molten rosin. These collectively furnish the criterion governing the characteristics which the carton material must have, subject, of course, to the limitation that the carton material must be of adequate tensile strength.

As shown, the door member 20 is provided with hooks 41 and 42 adapted to fit into the eyes 43 and 44 fastened onto the side wall 23 of the supporting frame 16.

I claim:

1. The method of packaging rosin comprising

introducing rosin into a carton having a paper base as its essential constituent, the inner wall of the carton carrying a coating or impregnation of sodium silicate minimizing the absorption of the rosin by the carton material, the rosin while it is being introduced into the carton being maintained at a temperature between 150° F. and 350° F., and cooling and solidifying the rosin in said carton and closing the same.

2. A package comprising in situ solidified resin and a carton therefor provided with an inner liner carrying a coating or impregnation of sodium silicate minimizing the absorption of the resin at a temperature as high as 350° F., said coating being substantially insoluble in the resin.

3. A package comprising in situ solidified rosin and a carton therefor provided with an inner liner carrying a coating or impregnation of sodium silicate minimizing the absorption of the rosin at a temperature as high as 350° F., said coating being substantially insoluble in the rosin.

CHARLES CRUM GILLIGAN.

CERTIFICATE OF CORRECTION.

Patent No. 2,259,035.

October 14, 1941.

CHARLES CRUM GILLICAN.

It is hereby certified that the above numbered patent was erroneously issued to Charles Crum Gillican, of Homerville, Georgia, assignor, by mesne assignments, to The Glidden Company, of Cleveland, Ohio, a corporation of Ohio, whereas said patent should have been issued to Charles Crum Gillican, of Homerville, Georgia, assignor, by direct and mesne assignments, of one-half to The Rosa Company, of Homerville, Georgia, a corporation of Georgia, and one-half to The Glidden Company, of Cleveland, Ohio, a corporation of Ohio, as shown by the record of assignments in this office; and that the said Letters Patent should be read with this correction therein that the same may conform to the record of the case in the Patent Office.

Signed and sealed this 17th day of March, A. D. 1942.
